STRAINER FOR DRINKING VESSEL OR SIMILAR ARTICLE

Christopher Alexander, Long Island City, N. Y.

Application November 19, 1949, Serial No. 6,161

Term of patent 14 years

(Cl. D44—29)

To all whom it may concern:

Be it known that I, Christopher Alexander, a citizen of the United States, residing at Long Island City, in the county of Queens and State of New York, have invented a new, original, and ornamental Design for a Strainer for Drinking Vessel or Similar Article, of which the following is a specification, reference being had to the accompanying drawing, forming part thereof.

In the drawing

Fig. 1 is a perspective view of a strainer, showing my new design;

Fig. 2 is a top plan view thereof;

Fig. 3 is a side view; and

Fig. 4 is a side view taken at right angles to the view of Fig. 3.

I claim:

The ornamental design for a strainer for drinking vessel or similar article, substantially as shown.

CHRISTOPHER ALEXANDER.
